Primary Examiner — Darlington Ly(74) *Attorney, Agent, or Firm* — Wood Herron & Evans LLP(57) **CLAIM**

The ornamental design for a vehicle grab handle, as shown and described.

DESCRIPTION

FIG. 1 is a top, front, and left side perspective view of a vehicle grab handle showing our new design;

FIG. 2 is a front and left side perspective view thereof;

FIG. 3 is a rear and right side perspective view thereof;

FIG. 4 is a top, rear, and right side perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.
